W. FRÖHLICH

WATER CLOSET

Filed April 18, 1927

Fig. 1.

Fig. 2.

Fig. 3.

Inventor:

UNITED STATES PATENT OFFICE.

WALTER FRÖHLICH, OF BERLIN-WILMERSDORF, GERMANY.

WATER-CLOSET.

Application filed April 18, 1927, Serial No. 184,749, and in Germany April 28, 1926.

My invention relates to closets, more particularly water-closets, and consists of a device for raising and lowering the lid and the seat by means of special handles.

5 According to my invention each of these handles is located on the upright leg of a frame consisting of two such legs and a transverse wall bracket adapted to be adjusted at right angles to the wall.

10 In the drawing affixed hereto an embodiment of my invention is illustrated by way of example. In the drawing

Fig. 1, is a front-elevation,

Fig. 2, a side-elevation, and

15 Fig. 3, a plan of a water-closet to which my invention is applied.

Like parts are indicated by like letters of reference in all the figures of the drawing.

On the closet *a* is mounted a frame *b* 20 which is secured at the top by means of a forked wall bracket *c* adjustable at substantially right angles to the wall to adapt it to the location of the closet. At the sides of the frame *b* there are pivoted upon pins *d*

25 bell-crank levers *f* provided with handles *e* by means of which through the agency of

hinged rods *i* the lid *g* and the seat *h* may be raised and lowered at will.

Various changes may be made in the details without departing from the spirit and 30 the scope of the invention, and I desire, therefore, that only such limitations shall be placed thereon as are imposed by the prior art.

I claim as my invention:

35 In a water-closet, in combination, a bow-shaped frame mounted upon the closet, an adjustable wall bracket for securing the upper transverse member of said frame spaced from the wall, a bell-crank lever provided 40 with a handle mounted on one of the upright legs of said frame, a connecting rod pivoted to the free arm of said lever and the lid of said closet, a second bell-crank lever provided with a handle mounted on the other 45 upright leg of said frame, and a connecting rod pivoted to the free arm of said second lever and the seat of said closet.

In testimony whereof I have affixed my signature.

WALTER FRÖHLICH.
